(57) **CLAIM**

The ornamental design for a furniture panel as shown and described.

DESCRIPTION

FIG. 1 is a front perspective view of the furniture panel; FIG. 2 is another front perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The broken lines shown in the drawings illustrate portions of the furniture panel that form no part of the claimed design. The dash-dot-dash lines shown in the drawings represent illumination and these lines form no part of the claimed design.

1 Claim, 6 Drawing Sheets
